UNITED STATES PATENT OFFICE.

ABRAHAM J. SAWIN, OF SPRINGVILLE, CALIFORNIA.

PIPE-WRENCH.

SPECIFICATION forming part of Letters Patent No. 654,283, dated July 24, 1900.

Application filed April 8, 1900. Serial No. 11,362. (No model.)

To all whom it may concern:

Be it known that I, ABRAHAM J. SAWIN, a citizen of the United States, residing at Springville, in the county of Ventura and State of California, have invented a new and useful Pipe-Wrench, of which the following is a specification.

This invention relates to pipe-wrenches, and has for its object to provide certain new and useful improvements whereby the jaws are yieldingly held together for convenient adjustment and application to a pipe and also to bind firmly upon the latter during the operation of the wrench.

To these ends the present invention consists in the combination and arrangement of parts, as will be hereinafter more fully described, shown in the accompanying drawings, and particularly pointed out in the appended claims, it being understood that changes in the form, proportion, size, and minor details may be made within the scope of the appended claims without departing from the spirit or sacrificing any of the advantages of the invention.

In the drawings, Figure 1 is a perspective view of a pipe-wrench constructed in accordance with the present invention. Fig. 2 is a detail perspective view of the head end of the handle, the jaws being removed. Fig. 3 is a detail sectional view taken longitudinally through the jaws.

Corresponding parts in the several figures of the drawings are designated by like characters of reference.

Referring to the accompanying drawings, 1 designates the shank or handle of the wrench, having one end enlarged to form a transverse head 2, which is provided with a longitudinal bifurcation 3, forming the opposite ears 4, between which the jaws of the wrench are mounted.

The jaw 5 is bowed or hook-shaped, having its rear end received between the ears 4 of the head, located at one side thereof, and mounted to swing laterally upon a transverse pivot-pin 6. The opposite free end of the jaw is provided with an abrupt inwardly-extending shoulder 7. The other jaw 8 has its rear end received between the ears 4, located op-

posite the jaw 5 and mounted upon a transverse pivot-pin 9, so that both jaws may swing in the same direction transversely of the handle. The outer free end of the jaw 8 is adapted to coöperate with the shouldered free end of the jaw 5 and is serrated, as at 10, so as to bite into the pipe. An angular transverse groove 11 is formed across the free extremity of the jaw 8 and is tapered longitudinally, so as to receive a similarly shaped and tapered bit 12, the outer longitudinal edge of which projects through the entrance-opening of the groove. It will be understood that as one edge of the bit becomes worn the position of the latter may be changed, so as to present a new edge.

The opposite jaws are pivotally connected by means of a pair of links 13, located intermediate of the ends of the jaws and upon the outer sides thereof. The adjacent ends of the links are pivotally connected to the opposite ends of a common pivot-pin 14, extending transversely through the adjacent jaw and projecting at opposite sides thereof, so as to connect with the links.

Intermediate of the ends of the hook-shaped jaw 5 and in the inner side thereof there is provided a suitable socket or recess 15, through which one of the pivot-pins 14 passes. Mounted within this socket and embracing the pivot-pin is a coiled spring 16, having one arm 17 engaging against the rear wall of the socket and its opposite arm 18 extending out of the socket and connected to a transverse pin 19, extending between the opposite links 13 and located between the jaws.

From the foregoing description it will be apparent that the spring normally forces the free ends of the jaws together, so as to insure a positive grip upon the pipe and also yieldingly connects the jaws, so that the latter may be conveniently engaged with the pipe and, moreover, permits of a reverse movement of the wrench to obtain a new grip upon the pipe.

What I claim is—

1. A wrench, comprising a handle, a pair of jaws pivoted at their inner ends to the same end of the handle, and a yieldable spring connection for the jaws, said connection being

located between the jaws and also between the pivotal connections and the free ends thereof.

2. A wrench, comprising a handle, a pair of jaws pivoted thereto, opposite links pivotally connecting the jaws, a transverse pin connecting the links and located between the jaws, and a spring, comprising a coil located in a socket formed in one of the jaws and embracing the adjacent pivotal connection of the links, and opposite arms respectively en-

gaging a wall of the socket and the transverse pin, said spring normally forcing the jaws together.

In testimony that I claim the foregoing as my own I have hereto affixed my signature in the presence of two witnesses.

ABRAHAM J. SAWIN.
